DREGGE.

LUGGAGE CARRIER.

Application filed January 12, 1925. Serial No. 1,731.

This invention relates to a collapsible luggage carrier designed to be permanently attached to the outer edge of the running board of an automobile, and which can be 5 extended upwardly and locked in position when in service, being readily collapsible downwardly alongside of the outer edge of the running board when not in use, thereby occupying very little space and not appearing 10 at all noticeable on the running board when in collapsed position. It is a primary object and purpose of the present invention to construct a luggage carrier of this character which will be strong and rigid when 15 in extended operative position and substantially proof against accidental collapsing, yet one which may be very quickly and easily collapsed to inoperative position, wherein it will be inconspicuous on the running 20 board. The invention consists of many novel details of construction and arrangement of parts for practically and effectively attaining the above stated ends, as well as various others not at this time specifically 25 enumerated but which will appear as understanding of the invention is had from the following description taken in connection with the accompanying drawings, in which,

Fig. 1 is a perspective view showing the 30 luggage carrier in fully extended position attached to the running board of an automobile.

Fig. 2 is a perspective view, with a part 35 broken away and shown in section, illustrating the luggage carrier partly collapsed.

Fig. 3 is a fragmentary elevation of an 40 end portion of the luggage carrier extended, looking at the inner side of the carrier.

Fig. 4 is a transverse vertical section 45 through the running board, the carrier being shown in end elevation.

Fig. 5 is a fragmentary elevation of an 50 end portion of the carrier, the same being partially collapsed and the view showing the inner side of the carrier.

Fig. 6 is a fragmentary plan and horizontal section through the collapsed carrier showing the same collapsed at the edge of the running board.

Fig. 7 is a somewhat enlarged vertical 55 transverse section through the collapsed carrier, and

Fig. 8 is an enlarged perspective view indicating one form of detachable fastening

means which may be used in connection with 55 the end braces of the carrier.

Like reference characters refer to like parts in the different figures of the drawings.

The carrier is adapted to be connected at 60 the outer edge of the running board 1 of a motor vehicle, the same being disposed in automobiles between the front and rear fenders 2 and 3, as is well understood. Bars 4 shown at the under side of the foot board 65 may be used to connect the carrier to the foot board, at their outer ends extending a short distance beyond the edge of the foot board and carrying the lower horizontal member or rail of the carrier. This lower 70 rail includes a bar in the form of an angle iron having a horizontal leg 5 lying on and permanently secured in any suitable manner to the bars 4, and a vertical leg 6 spaced from the edge of the foot board and extending substantially the full width thereof. The carrier also has an upper member or rail including a bar also in the form of an angle iron having a horizontal leg 7 and 75 downwardly extending leg 8, which is located a very little farther outwardly than the leg 6 previously described, so that when the carrier is collapsed this leg 8 will pass along and outside of the leg 6 as shown in Fig. 7.

The lower angle member including the 80 legs 5 and 6 carries a second angle member having a horizontal leg 9 lying on and permanently secured in any suitable manner to the leg 5, while its vertical leg 10 is spaced a short distance from and extends upwardly 85 parallel to the leg 6 previously described. In like manner a second angle member is connected to the upper angle member of the structure having a horizontal leg located 90 against the under side of the leg 7 and permanently secured thereto by spot-welding, riveting or otherwise and having a vertical leg extending downwardly, paralleling the leg 8 and spaced farther therefrom than the 95 leg 10 is from the leg 6 (see Fig. 4).

At the ends of the upper and lower rails thus constructed, upper and lower links 13 and 14 are positioned, the same being pivotally connected together at their inner ends, 100 at 15, while at their outer ends they are pivotally connected, at 13^a and 14^a, respectively, to the before described legs 12 and 10, (see

Fig. 5). A horizontal bar 16 is also pivotally connected at the meeting ends of the links 13 and 14 by the same pivot 15 which connects them together. This bar extends inwardly and at its opposite end portion is provided with a substantially horizontal slot 17 which, at its outer end, is formed with an upper enlargement or short branch 18, as shown in Fig. 5. This structure is located at each end of the luggage carrier and is the same at both ends.

Set in a short distance from each end of the upper and lower rails of the luggage carrier are bars 19 and 20 which cross each other at their middles and are pivotally connected together at 21. The bars 19 at their upper ends are pivotally connected at 19^a to the legs 12 of the inner angle bars of the upper rail. Similarly, the lower ends of the bars 20 are pivotally connected at 20^a to the leg 10 of the inner angle bar of the lower rail of the luggage carrier. These legs 12 and 10 at the opposite ends of the cross bars 19 and 20 are slotted lengthwise, as shown at 23, and the lower end of cross bar 19 and the upper end of cross bar 20 are equipped with headed pins 19^b and 20^b, respectively, making slidable connections of the cross bars with said legs 12 and 10 at the slots therein. A horizontal bar 22 is pivotally connected at one end to one of the pairs of cross bars 19 and 20 by the pivot 21 and extends to the pivot 21^b of the opposite end pair of cross bars 19 and 20 at which end the bar is provided with a slot 22^a through which the pivot pin 21^b passes.

In addition between the end cross bars 19 and 20 another pair of similar cross bars 19^x and 20^x are pivotally connected together at their middle by a pivot 21^a which also passes through the horizontal bar 22. These bars 19^x and 20^x are pivotally connected at one end and slidably connected at the other to the upper and lower rails in identically the same manner as the bars 19 and 20 previously described.

With this construction when the luggage carrier is extended, as shown in Fig. 1, the links 13 and 14 are in vertical alignment, the bars 19 and 20 and 19^x and 20^x cross each other and the bars 16 have been moved outwardly to a position such that the shanks of the pins 21 may be received in the recesses or branches 18 of the slots 17 in the bars 16, thereby providing a positive lock against collapse of the carrier until such time as the inner ends of said bars 16 are moved upward slightly so as to bring the shanks of pins 21 in direct alignment with the slots 17. This unlocks the structure and by moving the links 13 inwardly the same are collapsed, as shown in Fig. 2. It is also evident that the bars 19, 20, 19^x and 20^x are also collapsed, during which action the pivots 21 and 21^b approach each other and

the pivot pin 21^b slides in the slot 22^a of the bar 22, permitting the upper rail to eventually reach a lower position wherein the upper horizontal legs 7 and 11 of the angle bars comprising said upper rail, bear against the upper side of the foot board, all of the collapsing link and bar structures between the upper and lower rails being housed within and entirely covered by said rails.

When the carrier is in fully extended position, as shown in Figs. 1, 3 and 4, it is desirable to reinforce and strengthen the carrier, particularly at its ends, so as to obviate outward bending or springing of the same. To this end a link bar 24 is loosely connected to an eye 25 which extends through and has pivotal connection with each link 13 adjacent the upper end thereof, said link bar at its free end having an opening 26 therethrough. Adjacent each end of the foot board 1 and near the inner edge thereof a metal plate 27 is securely fastened having its outer end turned upwardly at an angle as indicated at 28 from which a short pin 29 projects. This pin is adapted to pass through the opening 26 in the bar 24. To retain the bar in connection with the pin 29 a movable catch member 30 is pivotally connected at one end at 31 to and is located above the plate 27, it having an up-turned outer end 32 which may pass over the end of the bar 24 after it has been connected to the pin 29. Suitable friction detents 33 may be made on the plates 27 and 30 so as to hold the same against accidental disengagement from each other. The brace bars 24 serve not only to hold and reinforce the carrier but also provide obstructions at the ends of the carrier which prevent any luggage from moving outwardly at each end of the carrier, as is evident.

The structure described is relatively simple and can be manufactured at low cost. Various changes in detail may be resorted to without departing from my invention. Particularly the means used to detachably connect the free ends of the brace bars 24 to the foot board may be altered and changed without effecting or altering the operation of the construction. All of these changes in minor detail which come within the scope of the claims, defining the invention appended hereto are to be considered as comprehended by my invention.

I claim:

1. In combination with a running board of a motor vehicle, a fixed vertical rail attached at the edge of the running board and spaced away from said edge, a movable vertical rail located above and parallel to the fixed rail, a plurality of collapsible members joining the rails, whereby the movable rail may be moved away from or toward the fixed rail, and said collapsible members enclosed between the rails and edge.

of the running board, and means for locking said collapsible members and upper rail in upper extended position when the same are fully extended, substantially as described.

- 5 2. A luggage carrier comprising a lower rail including an outer and an inner angle iron member having horizontal legs in contact with and secured to each other and vertical legs extending upwardly and spaced 10 a short distance apart, the outer vertical leg of the outer member extending above the vertical leg of the inner member, an upper rail including two angle members having horizontal legs in contact and secured 15 together and downwardly extending vertical legs, the vertical leg of the outer member extending downwardly a distance farther than the vertical leg of the inner member and spaced farther from said vertical leg 20 of the inner member than the vertical leg of the outer member of the lower rail is from the vertical leg of the inner member thereof, said vertical legs of the inner members of the upper and lower rails lying in the same 25 plane, collapsible members pivotally connected together between their ends and connected at their ends to the vertical legs of the inner angle members of said rails, said collapsible members being collapsible where- 30 by the upper rail may be lowered into close engagement with the lower rail with the vertical legs of the outer angle members passing by each other and with the collapsible members within and wholly covered by said 35 rails, and means for locking said collapsible members and outer rail in fully extended position, substantially as described.

3. A luggage carrier comprising upper and lower rails, a pair of links pivotally 40 connected together at each end of the luggage carrier, said links at their outer ends being pivotally connected to the upper and lower rails, respectively, a plurality of cross bars pivotally connected together between 45 their ends located between the upper and lower rails, each of said cross bars at one end being pivotally connected to one of the rails and at its opposite end being pivotally and slidably connected to the opposite rail, 50 a horizontal bar pivotally connected at one end to the pivot which connects each of said pairs of links, said horizontal bar extending inwardly from each end of the carrier, and means at the inner ends of each of said horizontal bars adapted to engage with the pivot connecting the adjacent pair of cross bars when the carrier is in fully extended position to thereby hold the same in extended 55 position, substantially as described.

- 60 4. A luggage carrier comprising a lower horizontal rail, a plurality of pairs of cross bars located in spaced apart relation between said rails, said cross bars being pivotally connected together between their ends, the re- 65 spective bars of each pair being pivotally

connected at one end to the respective upper and lower rails and slidably connected at the other end to the opposite upper and lower rail, the pairs at the respective ends of the device being arranged so that their center 70 pivots will approach each other when the device is collapsed, and a horizontal bar pivotally connected at the pivot of the cross bars at one end of the device and slidably connected at the pivot of the cross bars at the 75 opposite ends of the device.

5. A luggage carrier comprising upper and lower rails, each formed of two angle iron members, said members of the lower rail being located one within the other and having horizontal legs contacting and permanently secured together and vertical legs extending upwardly, and the upper rail having inner and outer angle members with horizontal legs in contact and secured together, 80 and vertical legs extending downwardly, a plurality of pairs of cross bars pivotally connected together and disposed between the vertical legs of the inner angle members, one end of each bar of each pair of bars being 85 pivotally connected to a vertical leg of one of said inner angle members and the other end of each bar of each pair of bars having headed pins connected thereto, the vertical legs of the other inner angle member being 90 slotted to receive the shanks of said pins, and a pair of links located at each end of the luggage carrier, said links being pivotally connected together at their inner ends and having pivotal connection at their outer ends 95 to the vertical legs of said inner angle members, substantially as described.

6. A construction containing the elements in combination defined in claim 5, combined with a horizontal lock bar pivotally connect- 100 ed at one end to each of the pivots connecting the inner ends of said pairs of links, said lock bars extending inwardly and being longitudinally slotted adjacent their inner ends, the pivot passing through the cross 105 bars nearest the ends of the luggage carrier extending through said slots, each of said slots at its inner end being formed with an upwardly extending branch, substantially as and for the purposes described.

7. A luggage carrier comprising a lower horizontal rail, a plurality of pairs of cross bars located in spaced apart relation between said rails, said cross bars being pivotally connected together between their ends, the 110 respective bars of each pair being pivotally connected at one end to the respective upper and lower rails and slidably connected at the other end to the opposite upper and lower rail, the pairs at the respective ends of the 115 device being arranged so that their center pivots will approach each other when the device is collapsed, a horizontal bar pivotally connected at the pivot of the cross bars at one end of the device and slidably connected 120 to the respective ends of the device, the 125 horizontal bar being pivotally connected at the pivot of the cross bars at the other end of the device.

at the pivot of the cross bars at the opposite ends of the device, a pair of links located at each end of the luggage carrier, said links being pivotally connected at their adjacent ends and having pivotal connection at their outer ends to the respective upper and lower rails, and a horizontal locking bar pivotally connected at one end to each of the pivots

connecting the ends of the links, said locking bars extending inwardly and being longitudinally slotted adjacent their ends to slidably receive the pivot at the center of the cross bars nearest thereto, substantially as described. 10

In testimony whereof I affix my signature,
HERBERT GLASSPELL.
